UNITED STATES PATENT OFFICE

2,482,215

OIL BURNER

Peter Kephart Russell, Shippensburg, Pa.

Application December 13, 1946, Serial No. 716,049

2 Claims. (Cl. 158—4)

1

This invention relates to oil burners of the gravity feed type in which all mechanically operated instrumentalities are eliminated and in particular an oil burner in which the oil is fed into a down draught air duct and additional air or water is fed into the mixture of air and oil as the mixture reaches the ignition point in the combustion chamber.

In the usual type of mechanically operated oil burner the oil is atomized or in some cases volatilized by injection under pressure through a stationary or rotating nozzle or through a venturi, but this requires motors and pressure elements which are costly and require maintenance and this is objectionable particularly in rural communities. With these ends in view this invention contemplates an oil burner wherein the oil passes into a comparatively large down draught air duct, is ignited in the presence of water vapors wherein the oxygen and nitrogen of the air and oxygen and hydrogen of the water are liberated providing larger quantities of oxygen for combustion and the air, oil and water vapors are ignited under a shield and blown against the hot surface of a baffle wall in a furnace or the like.

The purpose of the invention is to provide a simple, efficient and noiseless oil burner wherein all mechanically operated parts are eliminated.

In the oil burner of this invention the gases of combustion ignite first with a blue flame under a shield, then burn with a yellowish flame at the end of the shield, and then as they impinge the hot surface of the bridge wall or baffle a white flame is produced wherein the maximum amount of heat units are produced from the oil or fuel.

The object of this invention is to provide a gravity feed oil burner in the form of a tubular air duct adapted to be installed in the usual residence furnace or heater into which oil may be fed outside of the furnace wall, and which is provided with means for supplying water vapors to the fuel in combustion.

Another object is to provide a gravity feed oil burner having an air duct in which air is drawn downward into the duct.

Another object is to provide means for feeding water in combination with a gravity feed oil burner wherein the water is first converted into steam and then volatilized as it is introduced into a mixture of air and oil.

Another object is to provide a gravity feed oil burner in which the products of combustion are ignited under a protecting shield.

A further object of the invention is to provide an oil burner for residence or industrial use in

2

which all moving parts are eliminated and which is of a simple and economical construction.

With these and other objects in view the invention embodies an air duct mounted in the wall of a furnace by a flange in which the outer end of the duct is flared outward and extends upward and a recess is provided in the lower part of the inner end with the upper part thereof extended and slightly flared outward, and in which oil and water connections are associated with the duct.

Other features and advantages of the invention will appear from the following description taken in connection with the drawings, wherein:

Figure 1 is a view showing a side elevation of a furnace with part broken away showing the burner installed therein.

Figure 2 is a view showing a cross section through the burner on line 2—2 of Figure 4.

Figure 3 is a sectional plan through the lower part of the furnace showing the burner therein.

Figure 4 is a longitudinal section through the burner with the furnace wall and connecting pipes broken away.

Referring now to the drawings wherein like reference characters indicate corresponding parts the oil burner of this invention comprises a tubular air duct 10 having a water jacket 11, and an oil supply tube 12, wherein the duct 10 is mounted in a front wall 13 of a furnace 14 through a flange 15.

The outer end of the air duct 10 is provided with an opening to the atmosphere through an outwardly flared neck 16 and the duct may be provided with a valve 17. The inner end of the duct 10 is formed with an extending or overhanging shield 18 which is flared slightly outward as shown in Figure 3. The duct extends inward through the front wall 13 of a furnace and a wall 19 may be positioned in front of the open end 40 of the duct wherein the burning gases heat the surface of the wall, and then the heat from the wall assists combustion by convection. Additional air may be supplied to the combustion area through an opening 20 in the floor 21 of the furnace.

The oil burner of this invention may be made of any suitable size and is adapted for use in various types of furnaces. The burner is installed in the lower part of the front wall of a furnace 50 with the ducts thereof sloping slightly downward as shown in Figure 1 and oil is supplied through the tube 12 which is provided with a control valve 22. As heat is generated in the furnace air will be drawn downward through the outwardly flared nipple 16 and the oxygen thereof will be liberated

to accelerate combustion. Water is supplied to the jacket 11 through a pipe 23 having a valve 24 therein and as the water enters the furnace front it will be converted into steam and as it passes out of the end of the jacket it will be in the form of a vapor.

Ignition takes place under the shield with the gases burning first with a blue flame, then with a yellowish flame, and then with a white flame as hereinbefore described. The supply of oil, air 10 and water may be regulated and controlled wherein combustion takes place with the greatest efficiency, and with the highest possible heat.

The oil burner is illustrated and described in the preferred form, however, it will be understood that changes may be made in the design and arrangement of the parts without departing from the spirit of the invention.

The burner is illustrated as applied to a residence or domestic heating plant, however, it may be made of any size and may be used in industrial or power plants, as may be desired, and for some uses the upper surface of the burner in the furnace may be insulated by a sheet or coating 25 of asbestos or the like which may be held by ribs 26 and 27 at the sides of the burner as shown in Figure 2.

What is claimed is:

1. A gravity feed liquid fuel burner for a furnace, said burner comprising an air tube of substantial diameter adapted to be installed through a sidewall of the furnace with its forward part projecting a substantial distance within the interior of said furnace, said air tube being substantially entirely open at its forward end and closed at its rearward end, the top of said forward end of said air tube being formed with a longitudinal extension extending forwardly into the interior of the furnace beyond said forward end of the air tube and functioning as a combustion shield, downdraft outside air inlet means on the portion of said air tube outside of the furnace, a moisture supplying water jacket coextensive with and surrounding the sides and the bottom of said air tube with its forward end terminating at the inward end of said air tube and being open, water inlet means on said water jacket outside of said furnace, and gravity oil feed means for said air tube comprising a forwardly declining oil nozzle traversing the top of said air tube between said 50

air inlet means and the furnace and opening at its lower end into said air tube.

2. A gravity feed liquid fuel burner for a furnace, said burner comprising an air tube of substantial diameter adapted to be installed through a sidewall of the furnace with its forward part projecting a substantial distance within the interior of said furnace, said air tube being substantially entirely open at its forward end and closed at its rearward end, the top of said forward end of said air tube being formed with a longitudinal extension extending forwardly into the interior of the furnace beyond said forward end of the air tube and functioning as a combustion shield, 15 downdraft outside air inlet means on the portion of said air tube outside of the furnace, a moisture supplying water jacket coextensive with and surrounding the sides and the bottom of said air tube with its forward end terminating at the inward end of said air tube and being open, water inlet means on said water jacket outside of said furnace, and gravity oil feed means for said air tube comprising a forwardly declining oil nozzle traversing the top of said air tube between said air inlet means and the furnace and opening at its lower end into said air tube, said air tube and water jacket being slightly forwardly declined, so as to accelerate gravity feed of the oil and water forwardly through said air tube and said 30 water jacket, respectively.
